DEVICE FOR PRODUCING EXTRUDED SHEET METAL.

1,423,361.

Specification of Letters Patent. Patented July 18, 1922.

Application filed June 25, 1919. Serial No. 306,546.

To all whom it may concern:

Be it known that I, ALBERT F. ROCKWELL, a citizen of the United States, and a resident of Bristol, in the county of Hartford and 5 State of Connecticut, have invented certain new and useful Improvements in Devices for Producing Extruded Sheet Metal, of which the following is a specification.

This invention relates generally to apparatus for reducing metal ingots to sheet form.

It has heretofore been the usual and common practice to produce sheet metal from the original ingots by a numerous and varied 15 series of rolling operations which have made the cost of production of the sheet metal finally obtained very high. Not only has the cost been excessive but for many purposes the quality of the sheet metal produced by 20 rolling processes has not been up to the rigorous standard desired. I have discovered that I can dispense with several steps in the ordinary process of reducing the ingot to sheet form, thus reducing quite materially 25 the cost of production, and in addition produce a sheet metal having greatly improved characteristics with relation to the quality of the metal in the final product. I succeed in reducing the ingot in a single operation to 30 a sheet having a thickness such that a minimum amount of rolling will suffice to reduce the metal to a sheet having any desired thinness, and accomplish this by making use of an extruding or squirting process in which a 35 billet of the desired metal is heated to a suitably plastic condition and forced under pressure to flow through a die which gives the emerging metal the desired conformation.

In the art of producing extruded metal, 40 great difficulty is found in obtaining a product in sheet form because of the impossibility of forcing plastic metal through an elongated slit with an even pressure throughout that will produce a sheet having uniform 45 and regular strength and homogeneity of texture. This is the case largely because of the different relation that must necessarily exist between the intermediate portions and end portions of the slit and the wall of the 50 pressure chamber. In addition, the elongated form of die opening requires a pressure chamber whose size is substantially greater, with a consequent need of enormous pressure, than the minimum size possible to

be achieved when the die opening is circular 55 in shape as used, for instance, in the production of seamless tubing by an extruding process with a relatively smaller expenditure of power. Furthermore, the known success that is had in the production of seamless 60 tubing by such processes, with the attendant advantages of enhanced and uniform quality and strength in the extruded metal, results in a product having characteristics that 65 make a satisfactory standard to be striven for in the production of extruded metal in sheet form. I have discovered that by combining certain steps in the operation of extruding metal in tubular form, with novel means for cleaving the tube as it issues from 70 the die and spreading it out into flat sheet form, I am able to produce extruded sheet metal having all the advantages in quality and strength of extruded seamless tubing. In order to obtain the ultimate product in 75 the form of a sheet rather than a tube, I provide means acting coincidently with the extruding operation for slitting the tubular wall of metal as it passes through the die. The slitting means consists of an outwardly 80 extending scoring projection formed along the length of the outer surface of the mandrel or inner die member. In order to insure the cleavage of the emerging tube along the scored line, I preferably form the outermost 85 end of the mandrel with an enlarged and preferably outwardly-expanded spreader member which operates to expand the tube as it is pushed outwardly over the spreader member occupying the position of a core, 90 and causes the scored tube to split along the scored line so as to present separated edges that can be readily engaged by suitable forming devices provided to open out the split tube and bring it to a flattened sheet 95 form.

In the drawings,—

Fig. 1 is a longitudinal vertical section of an extruding device embodying the invention and showing the apparatus in condition 100 to begin an operation;

Fig. 2 is a view similar to Fig. 1, showing the apparatus in the midst of an operation;

Fig. 3 is still another view similar to Fig. 1 showing the condition of the apparatus at 105 the completion of an operation;

Fig. 4 is a transverse vertical section taken along the line 5—5 of Fig. 1;

Fig. 5 is a transverse vertical section of the split-tube-shaped body formed by the apparatus; and

Fig. 6 is a view in perspective of means used for spreading the split tube into flattened sheet form.

In the drawings, I show a cylinder 1 in which a piston 2 is actuated by hydraulic or other suitable pressure to force a billet of metal 3 through a die 4 held in position at one end of the cylinder by means of a cap 5. The metal billets 3 are preferably formed to fit the interior of the cylinder 1 and are provided with longitudinally-arranged central openings through which a suitable mandrel 6, arranged to be detachably seated at one end in the piston 2, can be placed. The diameter of the mandrel 6 is somewhat less than that of the opening in the die 4 so that an annular die opening 7 is provided which imparts to the metal extruded therethrough a tubular or annular formation.

However, as it is an object of this invention to produce extruded metal in sheet rather than in tubular form, I provide means for scoring the body of metal as it passes through the annular die opening and also means for expanding the scored tube to cause it to break along the scored line and thus provide a longitudinally-split tube, and further means for spreading and flattening out the split tube into suitable sheet form for being passed between compressing rollers for reduction to a sheet of the desired gauge.

The scoring means referred to consists of a longitudinally-arranged scoring edge or rib which extends substantially along the entire length of the mandrel 6 in position to indent or score the inner surface of the tube-shaped member passing through the die opening. For the reason that it is not desirable to have the scoring rib 9 on the mandrel make contact with the inner surface of the die member 4, I do not provide for the complete severance of the wall of the tube by the scoring means, but preferably arrange that the scoring rib shall be spaced slightly from the die member. By this arrangement, I provide for the retention of a thin connecting strip of metal along the scored line which can be readily ruptured by the action of the tube-expanding member already referred to. This expanding member preferably takes the form of an inwardly-converging member 10 which is permanently secured to the outer end of the mandrel 6 and whose greatest diameter is sufficiently greater than that of the interior of the tube 11 issuing from the die to split it along the scored line in the manner indicated in Fig. 5 and form a substantial gap 12 which facilitates the opening out or spreading of the split tube into flat sheet form.

In the operation of the device a hollow

cylindrical billet 3 of the desired metal heated to a suitably plastic condition, which would ordinarily be indicated by a red heat, and formed to fit the interior of the cylinder 2, is placed in the cylinder, the mandrel 6 is fitted to the head 13 of the piston 2 and passed through the hollow billet and the die opening, as indicated in Fig. 1 of the drawings. The enlarged rear end 14 of the mandrel has a rectangular or equivalent cross-section to prevent rotation of the mandrel about its axis at the beginning of the scoring operation of the scoring edge. The establishment of the alinement of the scored line at the beginning of the operation is sufficient and the alinement thus established will be maintained throughout the operation because of the guiding action that takes place between the elongated scoring edge 9 and the groove which it forms in the face of the wall of the tube.

Pressure being applied to the piston 2 a flowing of the metal composing the billet is caused to take place through the annular opening provided for the purpose between the mandrel 6 and the die member 4. The movement of the metal through the die opening in contact with the mandrel causes a forward movement of the mandrel also, but at a proportionately much slower rate because of the retarding action of the relatively large base member 14 of the mandrel as compared with the size of the central opening in the billet. The result is that while the base member of the mandrel is slowly moving through the resisting mass of the billet the tubular extruded member is moving at a comparatively rapid rate over the enlarged spreading member 10 which acts to expand the tube 11 and cause the wall thereof to part along the line freshly scored by the edge 9.

By means of the forming rollers 15 illustrated in Fig. 6 of the drawings, the split tube 11 is spread and flattened out to the sheet form indicated by the flat strip 16. The strip 16 is in a satisfactory condition for passing between suitable rollers for reduction to the desired thickness.

It will thus be seen that I have succeeded in producing by an extruding process a metal blank having a suitable formation for subsequent rolling to its final sheet form. By making use of an annular die opening rather than the elongated straight slit that might be suggested by the cross-section of the metal strip finally obtained, I am enabled to produce, with a comparatively small and compact pressure cylinder, an extruded strip of relatively great width. In addition to this, by using the annular die opening, I obtain a metal blank with superior qualities as to uniformity and homogeneity of texture, for the reason that all portions of the opening are equidistant from

the corresponding oppositely-disposed portions of the cylinder walls, whereby a uniformity of flow and pressure through all portions of the opening is secured.

5 5. What I claim is:

1. In a metal working device, a die member having an opening through which the metal may be forced in a tubular formation, and means for cleaving the wall of the tube 10 as it passes through said opening.

2. A device for reducing metal to sheet form comprising: a die member having a die opening of annular formation, means for forcing the metal to be reduced through 15 said die opening, and means for cleaving the metal to produce a blank having the formation of a longitudinally-split tube.

3. A device for reducing metal to sheet form comprising: a die member having a die 20 opening of annular formation, means for forcing the metal to be reduced through said opening, means in said opening for cleaving the metal as it passes therethrough to produce a blank having the formation of 25 a longitudinally-split tube, and means for causing the split tube to take the formation of a substantially flat sheet.

4. A device for reducing metal to sheet 30 form comprising: a die member having a die opening of annular formation, means for forcing the metal to be reduced through said annular opening, means for scoring the metal as it passes through said opening, means for expanding the tubular body 35 of metal and causing it to part along the scored line produced by said scoring means to thereby produce a longitudinally-split tube, and means for flattening out the split tube into sheet form.

40 5. A device for reducing metal to sheet form comprising: a die member having an opening, means for forcing the metal to be reduced through said die opening, a mandrel arranged to occupy a position in said 45 die opening to form an annular passage through which the metal is forced, and means for cleaving the metal as it passes through said annular passage.

6. A device for reducing a metal billet to 50 sheet form comprising: a cylinder having a die opening at one end, a piston arranged to operate in said cylinder and to force the metal contained in a billet placed in said cylinder through said die opening, a mandrel detachably mounted at one end in the 55 face of said piston and extending forwardly through a passage provided for the purpose in the billet and through said die opening, said mandrel being smaller than said die opening to thereby form an annular passage 60 through which said metal is forced, means for cleaving the metal as it passes through

said annular passage, and means for spreading out the split tube into a flat sheet form.

7. A device for reducing a metal billet 65 to sheet form comprising: a cylinder having a die opening at one end, a piston arranged to operate in said cylinder and to force the metal contained in a billet placed in said cylinder through said die opening, a mandrel detachably mounted at one end in the 70 face of said piston and extending forwardly through a passage provided for the purpose in the billet and through said die opening, said mandrel being smaller than said die opening to thereby form an annular passage 75 through which said metal is forced, means for scoring the annular body of metal as it passes through said opening, means for expanding the tube to cause it to cleave along the scored line, and means for flattening out the split tube into flat sheet form.

8. A device for reducing a metal billet 80 to sheet form comprising: a cylinder having a die opening at one end, a piston arranged to operate in said cylinder and to force the metal contained in a billet placed in said cylinder through said die opening, a mandrel detachably mounted at one end in the 85 face of said piston and extending forwardly through a passage provided for the purpose in the billet and through said die opening, said mandrel being smaller than said die opening to thereby form an annular passage 90 through which said metal is forced, means on the mandrel for scoring the body of metal passing through said opening, means mounted on the outer end of the mandrel for expanding the scored tube and causing it to break along the scored line, and means for 95 rolling the split tube into flat sheet form.

9. A device for reducing a metal billet to 100 sheet form comprising: a cylinder having a die opening at one end, a piston arranged to operate in said cylinder and to force the metal contained in a billet placed in said cylinder through said die opening, a mandrel detachably mounted at one end in the 105 face of said piston and extending forwardly through a passage provided for the purpose in the billet and through said die opening, said mandrel being smaller than said die opening to thereby form an annular passage 110 through which said metal is forced, scoring means on the mandrel for scoring the body of metal passing through said opening, an inwardly-converging spreading member mounted on the outer end of the mandrel for expanding the scored tube and causing it to break along the scored line, and means 115 for flattening out the split tube into flat sheet form.

ALBERT F. ROCKWELL.
